UNITED STATES PATENT OFFICE.

ROBERT LESLIE MAPSON, OF LA MESA, AND ALBERT C. WOLFE, OF NESTOR,
CALIFORNIA.

GRAIN-ELEVATOR.

1,043,619.

Specification of Letters Patent.

Patented Nov. 5, 1912.

Application filed May 29, 1909. Serial No. 499,140.

To all whom it may concern:

Be it known that we, ROBERT LESLIE MAPSON, a citizen of the United States, and a resident of La Mesa, in the county of San Diego and State of California, and ALBERT C. WOLFE, a citizen of the United States, and a resident of Nestor, in the county of San Diego and State of California, have invented a new and Improved Grain-Elevator, 10 of which the following is a full, clear, and exact description.

Our invention relates to grain elevators, and has for its object to provide a conveyer and elevator adapted to be disposed at a plurality of angles relatively to each other, by means of which grain may be conveyed from a plurality of positions to be fed into a threshing machine which remains stationary, there being means connected with 20 the threshing machine adapted for driving the elevator and conveyer.

Still other objects of the invention will appear in the following complete description.

25 In this specification we will describe the preferred form of our invention, it being understood that the scope of the invention is defined in the appended claims.

Reference is to be had to the accompanying drawings forming a part of this specification, in which similar characters of reference indicate corresponding parts in all the views.

Figure 1 is a plan view of our invention 35 as applied to the conveyer; Fig. 2 is an enlarged plan showing the means for mounting the conveyer and the means for rotating the drum journaled therein; Fig. 3 is an enlarged sectional view on the line 3—3 of 40 Fig. 2; Fig. 4 is an enlarged sectional view taken on the line 4—4 of Fig. 1; Fig. 5 is a sectional view on the line 5—5 of Fig. 4, and Fig. 6 is a side view of Fig. 3 looking toward the right.

45 By referring to the drawings it will be seen that an elevator 10 is provided, which extends nearly to the ground and which is adapted to convey the grain upwardly to the threshing machine. A conveyer 11 is provided, which is constructed with drums 12 over which is disposed the usual conveyer belt 13. The inner terminal of the conveyer 11 is disposed above the outer terminal of the elevator 10 so that the material carried

by the conveyer 11 is dumped on the elevator to be lifted to the threshing machine, the elevator being constructed with the usual drums 14 and conveyer belt 15. Secured to the frame of the elevator there is a beam 16, which is disposed above the outer 55 terminal of the elevator. There is a recess 17 in the upper face of this beam 16 near its outer terminal, and over this recess 17 is disposed plate 18 having an orifice therein, which serves as a journal for the central 60 vertical shaft 19, the lower terminal of this central vertical shaft 19 being spaced from the sides of the recess 17, and as the central vertical shaft 19 does not fit the orifice in the plate 18 tightly, there is some room for 65 lateral play of this central vertical shaft.

The conveyer 11 has a plate 20, which projects outwardly, and which has an orifice in which is disposed the central vertical shaft 19, and the conveyer 11 also has a beam 21 75 having an orifice through which the central vertical shaft 19 is also disposed. Between the plate 20 and the beam 21 a casing 22 is disposed. This casing 22 has upper and lower members 23 in which there are orifices 80 through which central vertical shaft 19 is disposed. A supporting plate 24 is provided, this supporting plate 24 having a flange 25, which is bolted to the beam 16, the supporting plate 24 also having a slot 26 85 in which is disposed a pin 27, the pin 27 being secured to a bearing support 28 mounted on the casing 22. This construction permits of the vertical movement of the casing 22 with the bearing mounted thereon, but 90 prevents any lateral movement.

In a bearing 29 is journaled a horizontal shaft 30, this horizontal shaft 30 having a bevel gear 31, which meshes with a bevel gear 32 secured to the central vertical shaft 95 19. The central vertical shaft also has a bevel gear 33, which meshes with a bevel gear 34 on a shaft 35, which is journaled in bearings 36 mounted on blocks 37 secured to the obliquely disposed beams 38 and to 100 the transverse beams 39, which form part of the upper frame of the inner terminal of the conveyer.

To the side of the conveyer are secured bearings 40 in which is journaled a shaft 41, 105 this shaft 41 having a bevel gear 42, which meshes with the bevel gear 43 on the shaft 35, the shaft 41 also having a lower bevel

gear 44, which meshes with a bevel gear 45, secured to a shaft 46 to which the drum 12 is also secured.

The inner end of the conveyer 11 has standards 47 at either side, and these standards 47 are connected near their upper terminals by transverse beams 39, these transverse beams 39 having secured to them longitudinally of the conveyer a central beam 48, the plate 20 being bolted to the central beam 48. To the top of the standards 47 farthest from the central vertical shaft 19 are secured the obliquely disposed beams 38, said beams 38 converging toward the central vertical shaft 19 through an opening in which the vertical shaft is disposed. The shaft 30 is connected with the driving shaft 49 by a universal joint 50, the driving shaft 49 being connected with the threshing machine 20 so that it may be driven thereby.

When using our invention the shaft 49 is driven by the threshing machine, and it drives the shaft 30, which drives the central vertical shaft 19, which drives the shaft 35, which drives the shaft 41, which in turn drives the shaft 46 on which the drum 12 is mounted, the shaft 49 as stated being connected with the shaft 30 by a universal joint 50, and the other shafts being connected by a 25 gearing and the conveyer belt 13 is mounted on the drum 12. When the mechanism just described is in operation, the conveyer belt is driven by the threshing machine and it carries the grain toward the outer end of the 30 elevator, on which the grain is adapted to be lifted by the elevator into the threshing machine. When all the grain has been removed from both sides of the conveyer, its position may be readily changed without 35 disturbing the threshing machine or the elevator, since it is only connected to the elevator by means of the beam 21 and the plate 20, which are mounted on the central vertical shaft 19. It is therefore possible to move 40 the conveyer to a new position, as it readily swings with the central vertical shaft 19 as a pivot. No matter in what position the conveyer may be disposed from a position at right angles to the elevator at one side to a 45 position at right angles to the elevator at the opposite side, the machinery for the mechanism for driving the drum 12 will be in operative position, and since there is some play for the central vertical shaft in the 50 plate 19 with reference to the several members through which it is disposed, it is possible to adjust the conveyer on uneven ground with the plane of the bottom of the conveyer at various angles with reference to 55 the beam 16.

Having thus described our invention, we claim as new and desire to secure by Letters Patent:

1. In a grain feeder, a conveyer, an arm, 65 the conveyer being adapted to be disposed at

a plurality of angles relatively to the arm, a shaft supported on the arm and adapted to rotate relatively thereto, a casing having orifices through which the shaft extends, the conveyer having two members disposed respectively above and below the casing and mounted on the shaft, a bearing mounted in the casing, a second shaft journaled in the bearing, gearing connecting the first and second shafts, a support secured to the arm, a pin and slot connection between the support and the bearing, and means by which the first-mentioned shaft is adapted to operate the conveyer.

2. In a grain feeder, a conveyer, an arm, 80 the conveyer being adapted to be disposed at a plurality of angles relatively to the arm, a vertical shaft supported on the arm and adapted to rotate relatively thereto, a casing free from the conveyer, having upper and lower members provided with orifices through which the shaft is disposed, the conveyer having members disposed above and below the casing respectively and mounted to turn on said shaft, a bearing mounted on 85 the casing, a horizontal shaft journaled in the bearing, gearing connecting the two shafts, means to prevent the lateral movement of the bearing relatively to the arm, a shaft journaled in the conveyer, and means 90 by which the first-mentioned shaft is adapted to rotate the last-named shaft in the conveyer.

3. In a grain feeder, a conveyer, an arm, 100 the conveyer being adapted to be disposed at a plurality of angles relatively to the arm, a shaft supported on the arm and adapted to rotate relatively thereto, a casing having orifices through which the shaft is disposed, a bearing mounted on the casing, a second shaft journaled in the bearing, a gearing connecting the two shafts, two members of the conveyer having orifices therein, the members being disposed above and below the casing respectively, the first shaft passing 105 through the orifices in the members, means to prevent the lateral movement of the bearing, a shaft journaled in the conveyer, and means by which the first shaft is adapted to rotate the last-named shaft.

4. In a grain feeder, a conveyer, an arm, 110 the conveyer being adapted to be disposed in a plurality of angles relatively to the arm, a shaft supported on the arm and adapted to rotate relatively thereto, a casing having 115 orifices through which the shaft is disposed, members of the conveyer being disposed above and below the casing respectively, there being orifices in the said members through which the shaft is disposed, a bearing mounted on the casing, a second shaft journaled in the bearing, a gearing connecting the two shafts, means to prevent the lateral movement of the casing, a third shaft, a gearing connecting the first and 120

third shafts, a fourth shaft, a gearing connecting the third and fourth shafts, a shaft journaled in the conveyer, and a gearing connecting the fourth shaft with the shaft 5 in the conveyer.

5. In a grain feeder, a conveyer having spaced members provided with orifices, a vertical shaft passing through the orifices in the said members, a gear wheel secured to the vertical shaft, an arm, on which the shaft is supported, a bearing, means for supporting the bearing on the arm with a limited vertical movement relatively thereto, a second shaft journaled in the bearing, a 10 second gear wheel secured to the second shaft which meshes with the first-mentioned gear wheel, and means by which the vertical shaft is adapted to operate the conveyer.

6. In a grain feeder, a conveyer, an arm, 20 a shaft supported on the arm, a gear wheel secured to the shaft, a bearing, a supporting plate having a flange secured to the arm, a pin and slot connection between the bearing and the supporting plate, a second shaft 25 journaled in the bearing, a gear wheel on the second shaft which meshes with the first-mentioned gear wheel, and means by which the first-mentioned shaft is adapted to operate the conveyer.

30 7. In a grain feeder, a conveyer having a member with an orifice, an arm provided with a recess in its upper face, a vertical shaft extending at its lower end into said recess in the arm, the said shaft being 35 mounted to rotate relatively to the said arm and extending through the orifice in the said member of the conveyer, the said member of the conveyer being supported by the arm, a bearing connected with the said arm, 40 a horizontal shaft journaled in the bearing and gearing with the vertical shaft, a second horizontal shaft gearing with the vertical shaft, a horizontal shaft to which the conveyer drum is secured, and a second vertical 45 shaft gearing with the said horizontal shaft and the shaft of the conveyer drum.

8. In a grain feeder, a conveyer having a member with an orifice, an arm, a bearing on the arm, the conveyer being adapted to 50 be disposed at a plurality of angles relatively to the arm, a vertical shaft journaled in the bearing and adapted to rotate relatively to the arm, the vertical shaft being disposed through the orifice in the member 55 of the conveyer which is supported by the

arm, a second bearing, a supporting plate secured to the arm, a pin and slot connection between the second bearing and the said supporting plate, a second shaft journaled in the bearing, gearing connecting the first 60 and second shafts, and means by which the first-mentioned shaft is adapted to operate the conveyer.

9. In a grain feeder, a conveyer having two spaced members projecting therefrom 65 and provided with orifices, an arm, a bearing on the arm, the conveyer being adapted to be disposed at a plurality of angles relatively to the arm, a vertical shaft journaled in the bearing and adapted to rotate relatively to the arm, the vertical shaft being disposed through the orifices in the members of the conveyer, a casing located between the said members of the conveyer and having an orifice through which the vertical shaft is 75 disposed, a bearing on the casing, means on the arm to prevent the rotation of the casing relatively thereto, a second shaft journaled in the bearing on the casing, gearing connecting the first and second shafts, and means by which the vertical shaft is adapted 80 for operating the conveyer.

10. In a grain feeder, a conveyer having members provided with orifices, an arm, a bearing on the arm, the conveyer being 85 adapted to be disposed at a plurality of angles relatively to the arm, a vertical shaft journaled in the bearing and adapted to rotate relatively to the arm, the vertical shaft being disposed through the orifices in the 90 members of the conveyer, a casing having orifices through which the vertical shaft is disposed, the said casing being located between the said members of the conveyer, a bearing on the casing, a supporting plate 95 secured to the arm, a pin and slot connection between the casing and the supporting plate, a second shaft journaled in the bearing, gearing connecting the first and second shafts, and means by which the vertical 100 shaft is adapted for operating the conveyer.

In testimony whereof we have signed our names to this specification in the presence of two subscribing witnesses.
